UNITED STATES PATENT OFFICE.

GEORGE ROTTMAN, OF NEW YORK, N. Y.

ENVELOP-CLASP.

1,253,427.

Specification of Letters Patent. Patented Jan. 15, 1918.

Application filed February 27, 1917. Serial No. 151,178.

To all whom it may concern:

Be it known that I, GEORGE ROTTMAN, a citizen of the United States, and a resident of the city, county, and State of New York, have invented certain new and useful Improvements in Envelop-Clasps, of which the following is a specification.

My invention relates to envelop clasps, and more particularly to that class of clasps in which the locking member revolves. The object of my invention is to provide a clasp of this type which may be opened and closed as many times as desired and which will not be released or opened accidentally if the envelop is sent through the mails or carried in the pocket. The envelop clasps in general use have metal locking members which are adapted to be bent over after being passed through the eyelet of the flap. The number of times which such clasps can be opened and closed is necessarily limited because the metal is bent each time. Furthermore, the ends of the clasp often catch in other envelopes and papers. In the present device the clasp member turns on a pivot and therefore it may be opened and closed any number of times without appreciable wear, and the ends are so disposed that they will not catch on other envelopes, or papers. The clasp member is adapted to engage with the eyelet reinforcement in such a manner that the clasp member will not be accidentally turned while being handled or when the envelop is transmitted through the mail. The device is adapted for use on either extensible or non-extensible envelopes.

In the drawing forming part of this application,

Figure 1 is an elevation of an envelop embodying the features of my invention and it shows the clasp closed or locked.

Fig. 2 is a sectional view, taken on the line 2—2 of Fig. 1.

Fig. 3 is a sectional view taken on the line 3—3 of Fig. 1.

Fig. 4 is a sectional view taken on the line 4—4 of Fig. 1, but showing the envelop open.

Fig. 5 is an elevation of a modified form adapted for extension envelopes.

Fig. 6 is a sectional view taken on the line 6—6 of Fig. 5.

Fig. 7 is an elevation showing the flap open.

Fig. 8 is a sectional view taken on the line 8—8 of Fig. 5.

In the drawings I have shown an envelop 1 provided with the usual flap 2 and it is understood that the envelop may be of any shape desired. The present device is intended to hold the flap closed. In Figs. 1 to 4 the device is constructed as follows:

There is a washer 3 on the inner side of the material forming the body 1 of the envelop and this washer is unsecured to the material in order that it may revolve in relation to said body. There is preferably a washer or reinforcing member 4 secured to the body material on the outside and over the washer 3. These washers and the body 70 material have registering apertures 5. The clasp member 6 has a flat central portion 7 which rests against and turns on the reinforcing washer 4, and there is an eyelet 8 stamped from the clasp member and extending through the apertures 5 and turned over at the inside against the washer 3. The clasp member is adapted to turn on the eyelet and the washer 3 is free to turn with the eyelet, so that the latter will not tear 80 through the body material around the eyelet hole.

The flap 2 is provided with an elongated opening 9 in a position to correspond with the position of the clasp when the flap is closed, and the edge of this opening is reinforced by the member 10 which is preferably made of pressed board pasted or glued to the flap 2.

The clasp member 6 is bent upwardly 90 from the intermediate portion 7 at 11 and then it extends horizontally at 12 and at each side of the central portion 7 a distance just equal to the width of the reinforcement 10. It then turns downwardly at each end, as 95 shown at 13 so that this portion lies at right angles to the portion 12 and turns toward the outer side of the flap when the latter is in closed position.

To close the envelop the clasp is turned to 100 the dotted line position shown in Fig. 1, where it will be parallel to the flap opening 9, and then the flap is closed over the body 1, bringing the clasp through this opening. The clasp 6 is then turned until 105 it lies crosswise of the opening 9, whereupon the envelop will be locked closed. It will be noted that the bends 11 form shoulders which abut against the inner edges of the reinforcement 10 when in closed position. 110 Likewise, the bends 13 form shoulders which engage against the outer edge of the rein-

forcement when the clasp is in closed or locked position. When the clasp is moved from open to closed position or vice versa, the downturned ends 13 are forced to pass over the reinforcement 10 and the reinforcement or clasp must bend slightly in order to permit of this movement. The movement, therefore, as the clasp is turned on its pivot, is more or less resisted. This resistance is here depended upon to keep the clasp in closed or locked position, so that when the envelop is handled the clasp will not be accidentally opened. The ends of the clasp being turned down toward the flap they are not apt to catch on anything and be turned accidentally or be bent out of position.

With the flap opening 9 extending up and down, as in Fig. 1, the clasp has a vertical play therein so that if the envelop is slightly extended when filled the flap can accommodate itself thereto in relation to the clasp. It will be understood that the opening 9 could extend in a direction at right angles to that shown in Fig. 1, the other elements remaining the same, and then the play referred to would be eliminated. This might be preferable for non-extensible envelops.

In Figs. 5 to 8 I have shown a modified construction in which the clasp may slide as well as turn, to allow for any extension of the envelop. Herein there is a metal plate 14 secured to the body 1 by tongues 15 passing through the body and clenched inside. The plate 14, in this construction, has an opening or slot 16 but there is none in the body 1. The clasp 6 has an eyelet 8 passing through the slot 16 and washer 18; the clasp portion 7 sliding against the outer surface of the plate 14 while the washer 18 slides against the inner surface thereof. Otherwise the clasp is the same as in the previous form. The clasp may slide in relation to the plate 14 corresponding with the length of the slot 6 so that the flap may adjust itself to the envelop if the latter is extended. But whatever the position of the clasp along the slot 16 the flap will be held closed by the clasp.

I am aware that it has been proposed to use a turning clasp for closing envelops but without something to retain the clasp member in closed position it is unreliable because it is very apt to turn when the envelop is handled, thereby releasing the flap. When the present clasp is turned to closed position the shoulders 11, 13 engage the edges of the reinforcement 10 or 14 and tend to keep the clasp in position against accidental displacement.

Having described my invention, what I claim is:

1. The combination with an envelop and its flap, said flap having an opening to re-

ceive a clasp, and having a reinforcing member on the outside, a clasp member pivotally connected to the envelop and adapted to pass through said flap opening and to be turned crosswise thereof to lock the flap closed, said clasp member having an abutment portion adapted to engage said reinforcing member and to resist the turning of the clasp member when the latter is in locked position.

2. The combination with an envelop and its flap, said flap having an opening to receive a clasp and having a reinforcing member on the outside thereof and around said opening, of a clasp member pivotally connected to the envelop and adapted to pass through said flap opening and to be turned crosswise thereof to lock the flap closed, said clasp member having abutment portions adapted to engage on opposite edges of said reinforcing member and to resist the turning of the clasp member when the latter is in locked position.

3. The combination with an envelop and its flap, said flap having an elongated opening to receive a clasp, and having an exterior reinforcing member around said opening, of a clasp member having an eyelet portion extending through the envelop, a loose washer on the inside of the envelop and engaged by the inner end of said eyelet, a reinforcing washer secured to the outside of the envelop near the eyelet, said clasp member being adapted to revolve on said eyelet, the clasp being bent upwardly from the envelop on opposite sides of the eyelet to form abutments adapted to engage the inner edges of said reinforcing member and extending thence horizontally and having its ends bent downwardly toward the envelop to form other abutments for engaging the outer edges of said reinforcing member for the purpose set forth.

4. The combination of an envelop and its flap, said flap having an opening to receive a clasp and provided with an exterior reinforcing member for said opening, a slotted plate secured to the envelop, a washer or the like adapted to slide between said slotted plate and the envelop, a catch member having an eyelet portion extending through the slotted plate and engaging the washer, said clasp member having abutment portions adapted to engage the edge of the reinforcing member of the flap and adapted to resist the turning of said clasp when the latter is in locked position.

Signed at the city, county and State of New York this 23rd day of February, 1917.

GEORGE ROTTMAN.

Witness:

MARION R. DES MARETS.
